UNITED STATES PATENT OFFICE.

ALVIN J. PRICE, OF EASTON, PENNSYLVANIA.

MECHANICAL TOY.

1,200,021.

Specification of Letters Patent.

Patented Oct. 3, 1916.

Application filed October 25, 1915. Serial No. 57,858.

To all whom it may concern:

Be it known that I, ALVIN J. PRICE, a citizen of the United States, residing at Easton, in the county of Northampton and 5 State of Pennsylvania, have invented certain new and useful Improvements in Mechanical Toys; and I do declare the following to be a full, clear, and exact description of the invention, such as will enable others skilled in 10 the art to which it appertains to make and use the same.

This invention relates to improvements in mechanical toys of that type which employs a sounding device adapted to be struck 15 when the same is pushed or pulled along the ground.

The principal object of my invention is to provide a device of this character carrying a bell which will be readily sounded irrespective of the direction of movement of the 20 toy.

A further object is to provide an improved catch for raising the bell striker out of operative position, thereby preventing the 25 sounding of the bell, yet permitting the other parts of the toy to be operated.

With the above objects in view my invention resides in the novel features of construction, combination and arrangement of 30 parts which will hereinafter be more particularly described and claimed.

In the accompanying drawings: Figure 1 represents a side elevation of my improved toy; Fig. 2 is an edge view thereof; Fig. 3 35 is a detail edge view on an enlarged scale showing the bell striker raised out of operative position; Fig. 4 is a horizontal section on the line 4—4 of Fig. 3; Fig. 5 is a similar view on the line 5—5 of Fig. 1.

40 In the embodiment illustrated my invention comprises a handle 1 having its lower end apertured to receive a pivot bolt 2 by which a wheel 3 is rotatably mounted upon the end of the handle. This wheel 3 may 45 be of any preferred construction and formed either of metal or wood, as is desired. A pitman rod 4 is eccentrically pivoted on said wheel by one end, its opposite end being extended upwardly and adapted to slide in a 50 guide block 5. This pitman 4 is pivoted to the wheel intermediate the rim and the hub thereof and preferably on one of the spokes of said wheel. Any sort of pivot pin or bolt 55 may be used for this purpose. The end of the pitman which is adapted to slide in the guide block 5 is preferably reduced and

rounded as shown at 7, so that the same may more readily reciprocate in the circular opening in said block. As the wheel 3 rotates it is obvious that the pitman will change its 60 angle of relation to the handle 1, therefore I pivotally mount said guide block upon the handle by the pivot pin 8, thereby allowing said block to move with the pitman yet guiding the same as it reciprocates. 65

The upper free end of the pitman is provided with a set screw 9 by which the length of said pitman may be slightly increased to allow the same to more readily actuate the bell striker 10 which is here shown as a 70 substantially U-shaped member pivoted by the extremity of one arm at 11 to a bell carrying block 12 which is mounted upon the handle 1. The extremity of the other arm of the striker is enlarged as shown at 13 to form 75 a clapper to strike the bell 14 which is carried by said block 12.

From the foregoing description it will be seen that as the pitman rises, the set screw 9 will strike the lower rounded portion of 80 the U and force the bell striker to hit the bell 14 and sound the same. The end of the pitman forces the striker into contact with the bell at each revolution of the wheel 3 irrespective of the direction of rotation of 85 said wheel. That is, the toy may be pushed or pulled along the ground and the pitman will operate to actuate the bell striker.

The bell striker 10 is held in operative position by one arm 15 of the L-shaped pivoted 90 catch 16 which is mounted upon said block 12 adjacent the clapper 13 and the bell striker. This L-shaped catch is shown as formed of spring wire bent intermediate its ends to provide an opening for the reception 95 of a pivot screw 16'. The catch is prevented from dropping too low by the stud 17, thus holding the catch in correct position for maintaining the bell striker in its operative position. When, however, it is desired to raise the bell striker out of operative position, the catch may be swung upon its pivot 16', thus raising the clapper end of the striker 100 upwardly and moving the bottom of said striker out of contact with the set screw on the pitman. When in elevated position one end of the catch is adapted to spring into a notch 18, thus holding the same in this position. 105

110 It is obvious that I have provided an extremely efficient means for both holding the bell striker and elevating the same out of

operative position when it is desired to prevent the sounding of the bell. It is also desired to lay particular emphasis upon the pivoted guide block which is used in connection with the pitman.

5 I claim:—

1. In a mechanical toy, a handle, a wheel pivoted thereon, a sounding device on said handle, a striker for said sounding device, 10 a pitman eccentrically pivoted at one end to said wheel, means on the end of said pitman for lengthening the same to bring said end closer to the striker, said means being adapted to actuate the striker when the 15 wheel is rotated in either direction, and a guide pivoted to said handle and adapted to slidably receive the free end of said pitman.

2. In a mechanical toy, a handle, a wheel pivoted thereon, a sounding device on said handle, a striker for said sounding device, a pitman eccentrically pivoted at one end to said wheel, a set screw in the free end of said pitman to lengthen the same and bring 25 said end closer to the striker, said set screw being adapted to actuate the striker when the wheel is rotated in either direction, and a guide pivoted to said handle and adapted to slidably receive the free end of said pitman.

3. In a mechanical toy, a handle, a wheel pivoted thereon, a sounding device on said handle, a striker for actuating said device, a reciprocating member connected with 30 said wheel for operating said striker, and a catch carried by the handle, said catch normally retaining the striker in operative position, it also being adapted to move said

striker out of coöperation with said reciprocating member to prevent actuation of the 40 sounding device.

4. In a mechanical toy, a handle, a wheel pivoted thereon, a sounding device on said handle, a striker pivoted to said handle, a pitman eccentrically pivoted at one end to 45 said wheel, its opposite end being adapted to actuate said striker, a catch pivoted intermediate its ends to the handle, one arm of said catch normally retaining the striker in operative position, it also being adapted 50 to raise said striker out of coöperation with the end of said pitman to prevent striking of the sounding device, said handle being notched to receive one end of the catch when the same is in its last mentioned position. 55

5. In a mechanical toy, a handle, a wheel pivoted thereon, a sounding device on said handle, a striker pivoted to the handle, a pitman eccentrically pivoted at one end to said wheel, its opposite end being adapted 60 to actuate said striker, a guide on said handle and adapted to slidably receive the free end of said pitman, and an L-shaped catch pivoted intermediate its ends to the handle, said catch normally retaining the 65 striker in operative position, it also being adapted to raise said striker out of co-operation with the end of said pitman to prevent striking of the sounding device.

In testimony whereof I have hereunto 70 set my hand in presence of two subscribing witnesses.

ALVIN J. PRICE.
